UNITED STATES PATENT OFFICE.

JOHN A. ROSE, OF GRAND RAPIDS, MICHIGAN, ASSIGNOR TO THE GRAND RAPIDS CLOCK AND MANTEL COMPANY, OF SAME PLACE.

DESIGN FOR A MANTEL.

SPECIFICATION forming part of Design No. 28,370, dated March 8, 1898.

Application filed December 7, 1897. Serial No. 661,119. Term of patent 7 years.

To all whom it may concern:

Be it known that I, JOHN A. ROSE, a citizen of the United States, residing at Grand Rapids, in the county of Kent and State of Michigan, 5 have invented or produced a new and original Design for Mantels, of which the following is a specification.

The chief object of this design is to provide an ornamental mantel for fireplaces and analogous purposes which presents a characteristic and distinguishing appearance to the eye.

The leading feature of the design resides in a mantel comprising perpendicular ornamental pilasters, a mantel-shelf, an ornamental 15 mantel-top, and a frame inclining downwardly from the mantel-top to the mantel-shelf, the mantel-shelf and the inclined frame lying between the perpendicular pilasters and the mantel-top surmounting said pilasters.

20 In the accompanying drawings, Figure 1 is a front elevation of my new and original design for a mantel, and Fig. 2 is a perspective view of the same.

A represents the top of the mantel, and B represents the back.

C represents the inclined frame, extending from the top A down to the shelf D, the upper end of the frame C being inclined, as above described.

D represents the shelf.

G represents the grate; II, the grate-opening.

P P represent the pilasters.

The frame C is made secure to the body of the mantel, so that it forms a part of the 35 mantel.

What I claim is—

The design for a mantel herein shown and described.

In witness whereof I have hereunto set my 40 hand and seal in the presence of two witnesses.

JOHN A. ROSE. [L. S.]
